UNITED STATES PATENT OFFICE.

DAVID STOLTZ, OF SAN FRANCISCO, CALIFORNIA.

HAIR-DYE.

SPECIFICATION forming part of Letters Patent No. 313,121, dated March 3, 1885.

Application filed November 30, 1883. (No specimens.)

To all whom it may concern:

Be it known that I, DAVID STOLTZ, of the city and county of San Francisco, State of California, have invented an Improvement in 5 Hair-Cosmetics; and I hereby declare the following to be a full, clear, and exact description of the manner in which I proceed to compound the different ingredients composing my cosmetic.

10 My invention relates to improvements in cosmetics for the hair; and it consists, essentially, in a compound of nitrate of silver, ammonia, extract of walnut, beeswax, and some fatty matter—such as cocoa-butter—the whole 15 rendered of such consistence as to admit of being put in the form of short sticks for use.

The object of my invention is to provide a hair-cosmetic that will restore the color, soften and render more tractable, and at the same 20 time impart to the hair a rich glossy appearance.

I take one-eighth of a pound of walnut-bark and treat with one-eighth of a pound of ammonia—such as spirits of hartshorn—thereby 25 obtaining an extract of walnut with a certain proportion of ammonia. With this I mix one-fourth of a pound of nitrate of silver and one and one-half pound of a mixture of beeswax and cocoa-butter in equal proportions. The 30 whole is thoroughly stirred and heated to sufficient temperature to render the mass homogeneous, when it is poured into molds and allowed to cool, the presence of the beeswax

causing the compound to become on cooling of the desired consistence. Other fatty substances or pomades may take the place of the 35 cocoa-butter; but I prefer the latter.

The cosmetic may be molded into any desired form for individual use, though it is preferably put up in small packages or sticks cov- 40 ered with tin-foil.

The principal feature in my cosmetic is the presence of the extract of walnut, which, combined with the nitrate of silver, imparts to the hair a more permanent and richer dye 45 than is possible where the nitrate of silver alone is used as the dyeing agent.

The advantage of a cosmetic having dyeing properties and put up in the form of sticks is, that the dye is applied directly to the hair, 50 and does not come in direct contact with the scalp and the roots of the hair, as is unavoidable in the use of liquid cosmetic dyes.

Having thus described my invention, what I claim as new, and desire to secure by Letters 55 Patent, is—

A hair-dyeing cosmetic consisting of nitrate of silver, ammonia, extract of walnut, and beeswax, in combination with some fatty substance, as set forth. 60

In witness whereof I hereunto set my hand.

DAVID STOLTZ.
